UNITED STATES PATENT OFFICE.

JOSEPH A. HOFMANN, OF MILL VALLEY, CALIFORNIA.

BUILDING CONSTRUCTION.

No. 893,924.

Specification of Letters Patent.

Patented July 21, 1908.

Application filed September 13, 1907. Serial No. 392,798.

To all whom it may concern:

Be it known that I, JOSEPH A. HOFMANN, citizen of the United States, residing at Mill Valley, in the county of Marin and State of California, have invented new and useful Improvements in Building Construction, of which the following is a specification.

My invention relates to an improved earthquake-proof, fire-proof and wind-proof building construction. Its object is to provide a system of construction suitable for chimneys, walls, columns and other structures which will have such inherent rigidity and stability independent of the cement and mortar, that the latter will not be the chief means, as it is nowadays, for holding the bricks together.

The invention consists of the parts and the construction and combination of parts as hereinafter more fully described and claimed, having reference to the accompanying drawings, in which—

Figure 1 is a perspective view embodying the invention. Fig. 2 is a plan view of a fragment of a wall. Fig. 3 is a vertical cross section. Fig. 4 is a perspective view of a block or brick. Figs. 5—6—7 show various types of bond-irons.

The invention comprises the use of a series of blocks, as A, which blocks have each a central vertical perforation 2, and one or more vertical end and side grooves 3; and some of the blocks have the top or bottom grooves 4. Where the blocks are used for facing the corner of a building, only one end and one side, or possibly one side only, or one end only, would have the grooves 3. These blocks are laid up in usual break-joint courses, with a suitable filling of cement or mortar; and metal rods, as 5, are passed up and through certain of the blocks and between other blocks, and these rods are bonded together by suitable bond-irons 6 or 7. Where bond-irons or rods, as 6, are used, 45 they usually seat in the grooves 4. Where flat bond-irons, as 7, are used, either horizontal or vertical, they being very thin, are accommodated in the spaces between the bricks. The bond-irons are made with eyes 50 or perforations 8 through which the rods 5 may pass.

The bricks or blocks can be made either of clay, cement or any other material of any size or shape best suited for the occasion.

55 The rods 5 can be made of steel, iron or any material of any size or shape desired (round,

square, polygonal etc.), each rod being embedded firmly in the foundations and continuing in one piece by welding or otherwise suitably joining successive sections together 60 as the courses in laying the bricks are reached, when building.

When the top of the building is reached the rods run through a plate of steel or iron, or any other material of any thickness desired, 65 and are then riveted or bolted firmly or fastened in any way most convenient. These rods can also run through a metal plate at each story if desired, especially when the brickwork acts as piers or columns 70 between the doors or windows. The walls are also strongly braced at each story by heavy metal rods or girders (not shown) but which give increased rigidity to the structure, especially in very tall buildings. 75

Preferably the blocks are centrally perforated as shown at 2, and are also vertically grooved on one or more ends or sides as shown at 3, so that the perforations and grooves will be brought easily into proper 80 register whether the bricks are laid one on the other or in break-joint formation, or at right angles to one another. It will thus be seen that the rods which pass through one brick pass outside of the immediate adjacent 85 upper and lower bricks.

Where piers are to be built, as at the corners or elsewhere, a hollow space, as 9, may be left, in which is disposed a metal column 10 which is cruciform in cross section. This 90 column 10 may be bonded to the bricks by ties 7, which have rods 5 passing through the eye at one end, and being riveted at the other end, as shown at 11, to the column 10. The edges of the column-shapes 10, fit correspond- 95 ing vertical grooves 3 in the adjacent blocks. This structure is particularly adapted for use in conjunction with a steel frame 12. In the elevation shown in Fig. 3 this steel frame is provided with lateral projecting plates 13 at 100 suitable intervals, say at each story, which extend part way between the courses of the brick, and are perforated to pass the vertical tie-rods 5. At a window opening, as shown at 14, the frame carries the top and bottom 105 plates 15; at these window openings the vertical tie-rods 5 are shorter, and are riveted at one end to these plates 15. The plates 15 are suitably sheathed in mortar, or other fire-proofing material, to protect the metal 110 from heat in case of fire. At occasional intervals the metal frame 12 is bonded to the

vertical rods 5 by suitable ties 7, as shown in Fig. 1.

The pier columns 10 may be arranged at more or less frequent intervals in the walls 5 according to the character of the building and the strains it may have to undergo. A structure of perforated bricks such as here shown, bonded together in the manner indicated; has an extreme of rigidity and 10 staunchness and is capable of withstanding the severest shocks, twists and strains. It renders high buildings proof against the forces of the heaviest winds and storms.

The perforated bricks with the vertical 15 rods and horizontal bonds produce an excellent chimney construction as shown in Fig. 1, at 16.

Having thus described my invention, what I claim and desire to secure by Letters Patent is—

1. In a building construction the combination with a steel frame, of perforated blocks laid one on the other, with the perforations 20 registering in vertical series, vertical rods passing through the perforations, metal connectors for tying said rods to said frame and to each other, and metal plates forming part

of the steel frame and extending at intervals into the brick structure and between courses of bricks, said plates having holes to receive 30 said rods.

2. A building construction consisting of perforated blocks laid one on the other with vertical rods passing through the perforations in the blocks, said blocks laid to inclose 35 a space, a metal shape, cruciform in cross section, fitting said space and metal bonds connecting said shape to said rods.

3. A wall construction consisting of perforated blocks with vertical rods passing 40 through the blocks, said blocks inclosing vertical pier spaces at intervals in the wall, and metal columns cross-shape in section fitting said spaces with the edges of said columns fitting corresponding vertical grooves in the 45 adjacent sides of the blocks, and metal bonds connecting the columns to said vertical rods.

In testimony whereof I have hereunto set my hand in presence of two subscribing witnesses.

JOSEPH A. HOFMANN.
